[57] CLAIM

The ornamental design for a bedstead, as shown and described.

DESCRIPTION

FIG. 1 is a front perspective view of a bedstead showing our new design;

FIG. 2 is a side elevation view, the opposite side being a mirror image thereof;

FIG. 3 is a front perspective view of the headboard section of our new design;

FIG. 4 is a front elevation view of the headboard section of our new design;

FIG. 5 is an enlarged partial perspective front view of the headboard section thereof;

FIG. 6 is a perspective view of the footboard section of our new design;

FIG. 7 is an elevation view of the footboard section of our new design;

FIG. 8 is a rear elevation view of the footboard section of our new design;

FIG. 9 is a partial top view of the headboard section;

FIG. 10 is a partial top view of the headboard section;

FIG. 11 is a partial top view of the footboard section; and,

FIG. 12 is a partial top view of the footboard section.

The broken lines are for environmental purposes only and form no part of the claimed design.

The bottom view and the rear view of the headboard section (not shown) form no part of the claimed design.
